HORIZONTALLY SWINGING BRACKET
SUPPORTED SEAT

James O. Templeton, Jr., Winchester, Tenn.

Application August 9, 1948, Serial No. 43,226

2 Claims. (Cl. 155—81)

1

This invention relates to a seat structure adapted to be secured to chairs used by dentists, barbers, etc. One of the objects of the invention is to provide a device of this kind adapted to be attached to the base or any other suitable part of a chair for dentists, barbers, etc., and which is constructed so that the operator will be required to only slightly bend the knees, when he wishes to sit.

Another object of the invention is to provide a seat construction of the character indicated above and adapted to place the operator close to the chair and the occupant thereof.

A further object of the invention is to provide a seat construction of the character indicated, which at all times will stay under the operator with a slight upward pressure regardless of the position at the chair he might assume either sitting or standing.

A still further object of the invention is to provide a seat construction of the character indicated above, permitting full freedom of foot movements of the operator.

An additional object of the invention is to provide a seat construction of the character indicated above adapted to be swung around the chair into an out-of-the-way position, and including a seat or stool adapted to be locked in a position remote from the chair.

The invention resides in the details of construction and in the combination and arrangement of the several parts of the improved seat construction whereby certain important advantages are attained, as will be hereinafter more fully set forth. It is, however, to be understood that the invention is not to be restricted or limited to the exact construction and combination of parts described in the following specification and shown in the accompanying drawings, but that such changes and modifications can be made, which fall within the scope of the claims appended hereto definitely pointing out the novel features of the invention.

In the several figures of the drawings similar parts are indicated by similar reference characters, and in order that my invention may be better understood, I will now proceed to describe the same with reference to the accompanying drawings wherein:

Figure 1 is a view in top plan illustrating a seat structure embodying the invention, a second position of certain of the parts being indicated by broken lines;

Figure 2 is a view partly in side elevation and partly in section of the structure as shown in Figure 1; and

2

Figure 3 is a detail sectional view taken substantially on the line 3—3 of Figure 1.

The seat construction as herein embodied comprises a comparatively deep socket 10 closed at one of its ends and provided with an outwardly extending flange 11 at the closed end portion. A plurality of equispaced holes 12 are arranged in the flange so that it can be secured to the bottom flange of a barber's or dentist's chair or to any other suitable part of such chair by means of bolts or the like. A pair of bearings 13 and 14 respectively are mounted inside the bore of the socket 10. An arm A has a shaft 15 formed integrally at one of its ends and the shaft extends 10 into the socket 10 and is rotatably supported in upright position by the bearings 13 and 14. Adjacent to the upper end of the shaft 15 the arm A has a comparatively short straight portion 16 extending at right angles to the shaft and the adjacent main portion 17 of said arm extends in a spiral curve upwardly and outwardly with respect to the end of the straight arm portion 16. At the uppermost end of the main arm portion 17 a short straight arm portion 18 is formed and a pedestal P is formed integrally with or is firmly secured to the outer end of the arm A. The upper portion 19 of the pedestal P extending over the biggest part of said pedestal is tubular and the lower portion 20 of the pedestal P is of a smaller diameter than the tubular top portion 19. The lower end portion of the smaller pedestal portion 20, is bifurcated as at 21 and a comparatively small wheel 22 is mounted rotatably between the bifurcations 21 and is adapted to roll about the axis of the shaft 15 on the floor supporting the chair to which the seat construction is attached.

The tubular pedestal portion 19 projects a comparatively short distance above the arm A and the thickness of the upper end portion 23 of the tubular pedestal portion 19 is outwardly increased as at 24 to create an enlarged upper end area on the tubular pedestal portion.

A seat supporting arm B comprises a shaft portion 25 extending into the tubular pedestal portion 19. A stop ring 26 is rigidly mounted on the shaft portion 25 adjacent to the lower end thereof, and a plurality of bearing members 27, such as balls or the like are arranged on top of said stop ring. A second stop ring 28 is mounted on the inner surface of the tubular pedestal portion 19 in any conventional manner at a comparatively small distance above the bearing members 27 and extends inwardly over said members but permits free passage of the shaft portion 25 of the arm B. A helical spring 29

which may be of round, or flat, stock, as preferred, is inserted into the tubular pedestal portion 19 and surrounds the shaft portion 25. The lower end portion of the spring 29 is suitably flattened and is fastened on said shaft portion above the second stop ring 28 by means of a screw 30 or the like engaging the shaft portion. A hole 31 is provided in the wall of the tubular pedestal portion 19 to permit the insertion of said screw 30. The upper end portion of the spring 29, which may also be suitably flattened, is secured to the wall of the tubular pedestal portion approximately at the level of the junction between the arm A and the pedestal P by means of a screw 32 inserted through a hole 33 provided in the wall of said pedestal portion and a hole 34 arranged in the shaft portion 25, and the screw 32 engages the wall of the tubular pedestal portion diametrically opposite to the hole 33 in said wall. An anti-friction bearing comprised in lower and upper annular elements 35 and 37, respectively, having ball bearings interposed therebetween, is mounted within the upper portion 19 of the pedestal above the screw 32 and in encircling relation with respect to the shaft 25. One of such elements is secured to the pedestal and the other one to the shaft 25.

When the shaft portion 25 of the arm B is arranged in the tubular pedestal portion as described, the arm portion 25 is held coaxially with and oscillatingly in said tubular pedestal portion by bearing members 27 and 36. At the same time the spring 29 urges the shaft portion 25 upwardly until the bearing members 27 contact the second stop ring 28.

The shaft portion 25 extends at a right angle to the main portion 38 of the arm B, which main portion is curved horizontally so that it extends toward the pivot axis of the arm A, when the arm B is connected with the arm A as described. On the free end of the main portion 38 an upward sleeve 39 is formed or secured and a support post 40 extends slidably through said sleeve. A seat 41 or a chair or the like is mounted in any conventional manner on the top end portion of the post 40. A set screw 42 extending through the wall of the sleeve 39 is adapted to engage the post 40 and secure it in any desired adjusted position. An outwardly extending flange 43 is formed or secured on the shaft portion 25 of the seat supporting arm B above the upper end of the tubular pedestal portion 19, and on the underside of the flange 43 a friction surface 44 is arranged by lining said under side of the flange B with a friction material 45 which may be of any suitable character such, for example, as rubberized cloth, a fiber sheet, or the like, or by roughening said flange underside. When the operator sits on the seat 41 the arm B is forced downwardly against the upward pull of the spring 29 until the friction surface 44 engages the top end surface of the tubular pedestal portion 19 and prevents free pivotal movement of the arm B about the axis of the shaft portion 25, of said arm. A pair of spaced apart lugs 46 are formed on the circumferential surface of the flange 43 and extends outwardly with respect to the arm A. A post-like stop member 47 is formed or secured on the upper end portion of the tubular pedestal portion 19 and protrudes upwardly therefrom between the two lugs 46, so that the movement of the arm B about the axis of the shaft portion 25 of said arm is limited by the contact of either one of the lugs 46 with the post-like stop member 47.

To limit the counterclockwise swinging of the 75

arm B, when desired, that is, the swinging of the arm toward the arm A, a stop member in the form of a lever 48 is provided with a slot 48' intermediate its ends, which is engaged on a pivot pin 48'' secured in the top side of the flange 43 and with a recess 49 in one of its ends which is adapted to be engaged with the stop pin 47 when the lever is aligned therewith and moved endwise for the purpose. Otherwise the recess is disengaged from the stop pin and the lever swung on the pivot pin to a position out of line with the stop pin.

A bracket C comprises a bracket bar 50 on one end of which a sleeve 51 is formed or secured. 15 A stud 52 or the like extends through the sleeve 51 and enters threadedly into the short straight portion 16 of the arm A from below securing the bracket bar 50 pivotally onto the the arm A. On the free end of said bracket bar a support hook 53 is rigidly secured and inwardly spaced from said hook, the bar 50 carries a pin or bolt 50a on which another support hook 54 is pivotally mounted. The two hooks extend toward each other and are adapted to support between them 20 a conventional electric foot switch 55. A pair of bolts 56 can be arranged to extend through the shanks of the hooks 53 and 54 to secure them in cooperative working position.

The above description shows clearly, that a 30 seat construction in accordance with the invention permits the operator to sit down by slightly bending his knees and that it will stay under the operator with a slight upward pressure regardless of the position he might assume at the chair, either sitting or standing.

I claim:

1. A seat structure adapted to be secured to the base of a dentist's chair and the like, comprising an upwardly angled arcuate arm adapted to partially encircle the chair, means for pivotally mounting the lower end portion of said arm for swinging movements about said chair, an upright pedestal rigidly connected with the upper end of said arm, a shaft depending within said pedestal, a second arcuate arm extending horizontally from the upper end of said shaft, and a seat supported on the free end of said second arm.

2. A seat structure as set forth in claim 1, wherein the said pedestal is tubular and has an upper portion of a greater diameter than the lower portion thereof to receive said shaft, the lower end of said lower portion being bifurcated, a roller journaled in said bifurcation, means supporting the shaft in the said upper portion for rotation, and adjustable means for regulating the extent of rotation of said shaft and the second arm relatively to the first arm and chair.
